(57) **CLAIM**

I claim the ornamental design for a toothbrush holder, as shown and described.

DESCRIPTION

FIG. 1 is a front view of a toothbrush holder showing my new design.

FIG. 2 is a left side elevation view of the toothbrush holder.

FIG. 3 is a rear elevation view of the toothbrush holder.

FIG. 4 is a right side elevation view of the toothbrush holder.

FIG. 5 is a top plan view of the toothbrush holder.

FIG. 6 is a bottom plan view of the toothbrush holder; and,

FIG. 7 is a perspective view of the toothbrush holder.

The broken lines show portions of the design that form no part of the claimed design.
